UNITED STATES PATENT OFFICE.

ROBERT A. ROBERTSON, OF NORMAN, OKLAHOMA.

SASH-HOLDER.

1,115,576.

Specification of Letters Patent.

Patented Nov. 3, 1914.

Application filed July 25, 1914. Serial No. 353,054.

To all whom it may concern:

Be it known that I, ROBERT A. ROBERTSON, a citizen of the United States, residing at Norman, in the county of Cleveland and State of Oklahoma, have invented a new and useful Sash-Holder, of which the following is a specification.

The present invention appertains to a sash holder, and aims to provide a novel and improved device for holding the sash of a window at the various positions to which it may be slid.

It is the object of the present invention to provide a sash holder which will be extremely simple and inexpensive in construction, which may be readily and inexpensively installed in various window constructions, which will be certain and uninterfered with in its operation, and which will also serve as an anti-rattler for the window sash.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention has been illustrated in its preferred embodiment in the accompanying drawing, wherein:

Figure 1 is a perspective view of the improved sash holder. Fig. 2 is a longitudinal section thereof as applied. Fig. 3 is a plan view of the device.

In carrying out the present invention, there is provided a relatively rigid bar or strip 1 which forms the body of the sash holder, a flat or leaf spring 2 fashioned from a strip of suitable resilient metal, and a flexible friction strip 3 constructed of textile material, fiber or the like. The bar or strip 1, leaf spring 2, and friction strip or facing 3 are secured together by means of a screw or other securing member 4 engaged through certain ends thereof, the said ends of the said members being fitted snugly together as seen in Figs. 1 and 2.

The leaf spring 2 is shorter in length than the bar or strip 1, and has its free end pointed, as at 5, while the friction strip 3 is slightly shorter than the spring 2, and has that end remote from the screw or securing member 4 secured to the free end portion of

the spring 2 by means of a rivet or other securing member 6. The friction strip 3 is adapted to be bowed or bent with the spring 2, and covers the outer side or face of the spring 2.

That end of the bar or strip 1 which projects beyond the free end of the spring 2, or which is remote from the securing member 4, is provided with a longitudinal series of outstruck spurs 7, which are offset from the plane of the bar or strip 1, and which are pointed and project toward the opposite end of the bar or strip 1. The outstruck spurs 7 provide the openings or apertures 8 in the bar or strip 1 into which the pointed free end of the spring 2 is projectable behind the spurs 7.

The series of spurs 7 and apertures 8 provide means for the adjustable engagement of the free end of the spring 2 with the bar or strip 1, to hold the spring 2 bowed more or less, according to the circumstances.

In applying the holder to a sash, the stile 9 of the sash is provided with a longitudinal recess or depression 10 adjacent the jamb 11 of the casing or frame, and the bar or strip 1 is seated snugly within the recess 10 against the bottom thereof. The screw 4 is then threaded into the sash to clamp the corresponding ends of the bar 1, spring 2 and friction strip 3 within the respective end of the recess 10. Then, by engaging the pointed end 5 of the spring 2 with the proper spur 7 and aperture 8, the spring 2 may be bowed properly in order that the friction strip 3 carried thereby will bear against the jamb 11 with sufficient pressure, to hold the sash in any position to which it is slid. It is understood, of course, that one of the holders may be employed upon each stile of a window sash, if desired, although one of the holders will suffice since the bowed spring 2 being under tension, will force the sash snugly within the sash-way 100 at the opposite side to assist in frictionally holding the sash at its various positions.

By engaging the pointed end 5 of the spring 2 with the various spurs 7 and apertures 8, the tension of the spring 2 may be 105 regulated as necessary to properly hold the sash raised and to enable the sash to be moved without difficulty, and furthermore, the adjustability of the free end of the spring 2 enables the holder to be applied 110 to various sashes, or in recesses 10 of various depths. The pointed end 5 of the

spring 2 being engaged behind one of the spurs 7 and into the corresponding aperture 8, will cause the free end of the spring 2 to bind in engagement with the bar or strip 1, 5 to hold the spring 2 in bowed condition, while the bar 1 will resist the straightening tendency of the spring 2.

The present holder will prevent the rattling of the sash, and will eliminate the 10 necessity of the usual pulleys, cords and weights employed for counterbalancing the sash, and which require considerable time and expense in their installation. The friction strip 3 will prevent the spring 2 from 15 scratching or marring the jamb, and will also frictionally engage the jamb 11 in such a manner as to hold the sash properly in place.

Having thus described the invention, what is claimed as new is:—

20

A sash holder embodying a bar, and a leaf spring having one end secured to one end of the bar and having its free end pointed, the bar having a longitudinal series of outstruck pointed spurs adjacent its 25 other end and providing apertures into which the pointed end of the leaf spring is engageable behind the said spurs.

In testimony that I claim the foregoing as my own, I have hereto affixed my signature in the presence of two witnesses.
